UNITED STATES PATENT OFFICE.

WILLIAM E. ARMACOST, OF COLUMBUS, OHIO, ASSIGNOR TO THE COLUMBUS TIRE & RUBBER COMPANY, OF COLUMBUS, OHIO, A CORPORATION.

DESIGN FOR A RUBBER TIRE.

57,759.

Specification for Design.

Patented May 3, 1921.

Application filed March 6, 1920. Serial No. 363,843. Term of patent 14 years.

To all whom it may concern:

Be it known that I, WILLIAM E. ARMACOST, residing at Columbus, in the county of Franklin and State of Ohio, a citizen of the United States of America, have invented a new, original, and ornamental Design for a Rubber Tire, of which the following is a specification, reference being had to the accompanying drawing, forming a part thereof.

Figure 1 is a top view of a section of the tire.

Fig. 2 is a cross section of Fig. 1.

I claim:

The ornamental design for a rubber tire as shown.

WILLIAM E. ARMACOST.

In the presence of—

F. W. GRUNERT,
A. C. MOORE.
